UNITED STATES PATENT OFFICE.

JOE LEN KILEY, OF HELOISE, TENNESSEE.

COTTON-PICKER'S BAG.

1,383,955.

Specification of Letters Patent. Patented July 5, 1921.

Application filed May 11, 1920. Serial No. 380,452.

To all whom it may concern:

Be it known that I, JOE LEN KILEY, a citizen of the United States, residing at Heloise, in the county of Dyer and State of Tennessee, have invented certain new and useful Improvements in Cotton-Pickers' Bags, of which the following is a specification.

This invention relates to sacks in which 10 cotton is gathered, and has for one of its objects to improve the construction and increase the efficiency and utility of devices of this character.

Another object of the invention is to provide a device of this character, open at the 15 ends to facilitate the discharge of the contents and with improved means for temporarily closing the lower end while the sack is being filled, and to temporarily close the 20 upper end during the transportation to the place of discharge.

Another object of the invention is to provide a device of this character including a tubular fabric body open at the ends and 25 reversible end for end, a support bearing upon the shoulders of the picker, means for detachably connecting the sack to the support, means for temporarily closing the lower end of the sack when being filled, 30 and means for temporarily closing the upper end of the sack after detachment from the support to protect the contents of the sack during transportation to the gin house or storage plant.

With these and other objects in view, the 35 invention consists in certain novel features of construction as hereinafter shown and described and then specifically pointed out in the claims, and in the drawings illustrative of the preferred embodiment of the invention.

Figure 1 is a perspective view of the improved sack with the upper end open, and the lower end closed.

Fig. 2 is a detail view enlarged of a part 45 of the lower portion of the sack closed and the fastening cord applied.

Fig. 3 is a transverse section on the line 3-3 of Fig. 1.

Fig. 4 is a transverse section on the line 50 4-4 of Fig. 1.

The sack is constructed of the usual material, such as canvas, and of the usual size, and comprises a back member 10 and a front

member 11 united at their edges only, leaving the ends open.

At each end the back portion 10 is provided with a plurality of loops 15, while the front portion 11 is provided with similar sets of loops 16 the loops being uniformly spaced so that the loops 15 will engage between the loops 16 when the ends are closed and thus placed in alinement, as represented in Fig. 2, to receive binding cords 17.

The loops are attached to the back and 65 front portion of the sack body at considerable distances from the ends to produce flaps 18 which overlap when the sack is closed, as shown in Fig. 4, to prevent the escape of the contents.

The sack is thus alike at both ends and is therefore reversible end for end.

The sack is designed to be supported from the shoulders of the picker, while being filled, and detachable therefrom when filled 75 and the open end closed, to hold the contents safely while being conveyed from the field to the gin house, or other places of discharge.

The shoulder engaging support comprises 80 a section of fabric 14 having a neck engaging band 12, preferably with an adjusting buckle 13. The member 14 extends normally at its lower end into the mouth of the sack when open, and is provided with 85 a plurality of loops 14' like the other loops, and adapted to be disposed in alinement with the series of loops 16 which for the time being are nearest thereto, to receive one of the holding cords 17, to hold the sack 90 in position while being filled.

One of the supports will be supplied to each picker, and any number of the sacks supplied therewith.

By this means, the picker, when he requires a sack picks up the first one at hand and attaches it without regard to its position end for end or front or back to the support 95 14. The end of the sack, which for the time being is downward, is closed by inserting one of the holding cords 17 through the interengaging loops, care being taken that the flaps 18 overlap, as shown in Fig. 4. The lower portion of the support 14 depends into the end of the sack which for the time being is uppermost, and thus prevents the cotton bolls from catching on the rear 100 upper loops when being inserted.

When the sack is filled the cord 17 which holds the sack attached to the support is withdrawn and the loops at the upper end of the sack interlocked and the cord applied thereto to close the sack as before described.

The picker then selects another empty sack and attaches it to the support and proceeds as before.

When ready to be discharged it is only necessary to withdraw the holding cord 17, at the bottom of the sack when the contents will drop out, or require only a slight shaking to accomplish this result.

It will be seen that I provide not only for the convenient filling and thorough securing of the sack, but for its expeditious emptying thus saving time, avoiding the heretofore common waste of cotton in carrying it from the field, because of inadequate fastening of the mouth of the sack, and lessening the chances of injury to the sack by tearing, such as frequently results when the sack has to be violently shaken in emptying it.

The preferred embodiment of the invention is disclosed in the drawings and set forth in the specification, but it will be understood that any modifications within the scope of the claims may be made in the construction without departing from the principle of the invention or sacrificing any of its advantages.

What I claim is:

1. A device of the class described comprising a tubular sack open at the ends and with a plurality of fastening devices attached to the sides of the sack and spaced

from its ends, the material of the sack in advance of the fastening devices foldable in superposed layers to form a closure to the sack and means for connecting the fastening devices from the opposite sides of the sack.

2. A device of the class described comprising a tubular receptacle open at the ends, a plurality of loops attached to each side of the receptacle and spaced from the ends, the loops at one side disposed opposite the spaces between the loops of the other side, so that when the sides are folded one over the other at one end the loops will interlock, and a holding cord extending through the interlocking loops.

3. A device of the class described comprising a tubular receptacle open at the ends, a holding member adapted to be disposed partly within the receptacle at one end to form a combined guide and guard flap, a plurality of loops attached to each side of the receptacle and spaced from the ends, the loops at one side disposed opposite the spaces between the loops of the other side, so that when the sides are folded one over the other at one end the loops will interlock, a plurality of loops attached to the flap and spaced from one end to engage in the spaces between one set of the loops of the receptacle, a binding cord extending through the interlocking loops at the end of the receptacle, and a binding cord extending through the interlocking loops of the flap and of the receptacle.

In testimony whereof, I affix my signature hereto.

JOE LEN KILEY.
